UNITED STATES PATENT OFFICE.

ISAAC STROUSE, OF NEW HAVEN, CONNECTICUT.

DESIGN FOR A CORSET.

SPECIFICATION forming part of Design No. 12,688, dated January 10, 1882.

Application filed December 15, 1881. Term of patent 7 years.

To all whom it may concern:

Be it known that I, ISAAC STROUSE, of New Haven, in the county of New Haven and State of Connecticut, have invented a new Design for Corsets; and I do hereby declare the following, when taken in connection with the accompanying drawing and the letters of reference marked thereon, to be a full, clear, and exact description of the same, and which said drawing constitutes part of this specification, and represents a side view, showing the hip-section complete.

This invention relates to a design for the ornamentation of that part of a corset commonly called the "hip-section"—that is to say, the part of the corset between the front and back, and which extends from under the arm down over the hip; and the design consists in the representation of cords or ribs in series, as shown in the accompanying illustration, and hereinafter described.

Transversely across the section is a series of ribs, *a*, at the bottom and *b* at the top, with intermediate transverse series, *c d*, leaving a space between the respective series. Between the series *a* and *d* is the representation of two

series of ribs, *e e*, running diagonally from the series *d* downward and backward to the series *a*, leaving plain spaces. The space between the series *d* and *e* is filled by a vertical series of ribs, *f*, and in the space between the series *b* and *c* are two diagonal series of ribs, *g g*, running diagonally from the series *b* downward and forward to the series *c*, leaving a plain space between them, as shown in the accompanying illustration.

35

I claim—

The design for the hip-section of a corset consisting of the transverse series *a b c d*, the space between the lower series and the next above showing diagonal series of ribs *e e*, with the plain space between them, the space between the series of ribs *c d* filled by a vertical series of ribs, *f*, and the space between the series of ribs *c* and *b* showing series of diagonal ribs *g g*, with a plain space between them, as shown 45 in the accompanying illustration.

ISAAC STROUSE.
